UNITED STATES PATENT OFFICE.

CHESTER H. THORDARSON, OF CHICAGO, ILLINOIS.

TRANSFORMER.

1,267,013.

Specification of Letters Patent. Patented May 21, 1918.

Application filed September 27, 1915. Serial No. 52,775.

To all whom it may concern:

Be it known that I, CHESTER H. THORDARSON, a citizen of the United States, and a resident of Chicago, in the county of Cook and State of Illinois, have invented certain new and useful Improvements in Transformers; and I do hereby declare that the following is a full, clear, and exact description thereof, reference being had to the accompanying drawings, and to the characters of reference marked thereon, which form a part of this specification.

This invention relates to improvements in electrical transformers, and refers to improvements in means for adjusting the transformer to potential drops along the transmission line, while at the same time maintaining the high and low tension windings in magnetic balance against the force 20 of the magnetic flux between the windings which tends to spread the windings and to disrupt the insulation.

Other objects of the invention are to simplify and improve the construction of 25 transformers, and the invention consists in the arrangement and combination of the parts shown in the drawings and described in the specification, and the invention is set forth in the appended claims.

Heretofore it has been a common practice 30 in connecting adjustable transformers along a high tension line to cut out or isolate one or more of the end coils of the primary or secondary winding to correspond to the line 35 drops, the coils thus cut out or isolated and also the next adjacent coils and the line being usually connected by tap-off wires to terminals, as at a terminal block, which wires are associated with bridging pieces or 40 jumpers, so that one or more of the end coils may be cut out of the active circuit.

This practice has developed a defect in 45 the operation of transformers in that it throws the primary and secondary windings out of magnetic balance thereby imposing unequal and excessive stresses on the windings and the insulating medium associated therewith.

In accordance with the present invention 50 I propose to cut out or isolate from the active circuit of the winding portions of the coils or winding units which are located mid-way between the ends of the winding, the number to be cut out depending upon 55 the potential drop at the particular point in the line at which the transformer is con-

nected. By thus arranging intermediate coils or winding units to be opened or cut out of the active circuit, I am able to maintain the output of the transformer substantially constant notwithstanding potential drops and, at the same time, to maintain the high and low tension windings in magnetic balance.

In the drawings:—

Figure 1 is a fragmentary diagrammatic view of the high and low tension windings of a transformer, showing my improvements applied thereto.

Fig. 2 is a diagrammatic view of another type of transformer showing the adjusting feature of my improvements applied thereto,

Fig. 3 shows a modification of the wiring of the high tension winding.

Fig. 4 is a detail showing the manner of connecting the grounded tap-off conductor to the outer sides of the low tension winding coils.

As shown in the drawings, 10 designates the primary winding and 11 the secondary winding of a transformer. 12 designates the core and 13 diagrammatically indicates the insulation between the transformer windings. In the type of transformer shown in Fig. 1, the primary winding is made up of a series of disk like units 14, 15, 16, 17 and 18 and the secondary winding may be made up of a series of like units 19, said units being formed, connected and insulated in a manner generally similar to the transformer construction shown in my prior application for U. S. Letters Patent, Serial No. 39,044, filed on the 10th day of July, 1915. It will be understood that in the diagrammatic illustration of the high tension units in Fig. 1 merely the upper cross sections of the coils or units are shown and that in the assembled structure the high tension winding coils surround the low tension windings and the core.

As shown in said Fig. 1, the adjustable feature of the transformer is arranged to cut or open four of the intermediate or central winding units 15, 16, 17 and 18 of the high tension winding. To the ends of each of the said units to be cut out and to adjacent active units of the primary winding are connected tap-off conductors 20 which lead and are respectively connected to clips 21 mounted on a suitably located terminal block 22. Said terminal clips are adapted to be bridged in pairs by bridging pieces

or "jumpers" 23, 24 of different lengths, as shown in Fig. 1.

If none of the coils or winding units are to be cut out of the active circuit the terminal clips are connected in series with the intermediate coils or units, so that the primary or high tension current traverses all of the coils or units of the primary winding. If it be assumed that one of the winding units is to be opened or cut out of the active circuit, the bridging piece associated with terminal clips thereof will be disconnected from the associated clips and a longer bridging piece will be inserted between the terminal clips connected to the tap-off wires 20 of one of the active coils or units and that of the next adjacent adjusting coil or winding unit. The primary current will thereafter be diverted around the isolated coil or winding unit. In like manner two or more central or intermediate winding units may be cut out of the active circuit by bridging between the different terminal clips of the series. The outermost clips of the series are respectively connected to winding units or coils which are intended to always remain in the active circuit.

In Fig. 2 my improvements are shown as applied to a type of transformer wherein the high and low tension windings, the latter not shown and the former designated by 25, are wound upon two legs 26 of the magnetic circuit which are connected by end pieces or yokes 27. In this instance the central coils or turns of the high tension winding are connected to tap-off conductors 28 to terminal clips 29 carried by the terminal block 30 and said terminals are adapted to be interconnected in the same manner as indicated in Fig. 1.

The foregoing illustrates the adaptation of my improved adjustment to two types of transformers, from which it will be clearly seen that the invention may be readily applied to other transformer types with the same result as to balancing the stresses due to magnetic flux between the transformer windings.

In Fig. 3 is shown a modified arrangement of the tap-off conductors, designated therein as 35. In this arrangement all of the conductors but the central conductor are made tubular and the conductors are arranged in concentric relation with certain of the conductors surrounding the others and insulated by insulating sleeves 36. In this construction said conductors 35 are connected by wires 37 with the intermediate adjusting coils and adjacent active coils of the high tension winding. The said tubular conductors are adapted to be connected together by different length bridging clips 38 39 of the form shown in Fig. 3 so that the intermediate adjacent coils or winding

units may be connected in series or one or more thereof cut out of the series in the same general manner as heretofore indicated.

Referring now to the low tension winding circuits and to the manner of connecting the same to the coils of the low tension winding and for connecting said coils or units with a grounded conductor, it will be noted that the coils or winding units 19 of the low tension winding are connected in pairs in multiple between the circuit wires 40, 41 of the low tension circuit. All the connections of the circuit wires to said coils are at their inner ends, and in the flat wire slab form of winding unit shown in my aforesaid prior application, said connections occur at the inner sides of the ring like slab units. 42 designates a grounded conductor that is connected to the outer sides of the low tension winding coils or units 19, the connection of said grounded conductor to the said low tension winding coils being at the parts of said coils nearest adjacent to the high tension winding. In this manner unusual stresses set up in the low tension winding are readily distributed so as not to produce destructive stresses in any part of the winding. The arrangement shown provides between the high and low tension windings an electro-static shield which protects the low tension winding from electro-static stresses developed in the high tension winding. Said shield is, in effect, divided into a large number of sections by reason of the independent connections of the several coils or units with the circuit and grounded conductors.

A means of practically connecting the outer sides of the coils or winding units to the grounded conductor 42 is shown in Fig. 4, where said grounded conductor has the form of a flat bar to which are soldered or otherwise secured the outer terminals 44 of said coils, adjacent coils being reversely wound, as indicated in Fig. 4.

The construction and arrangement whereby the low tension winding is protected from surges is not herein claimed but is made the subject of a divisional application, filed on the 23rd day of April, 1917, Serial No. 163,865.

I claim as my invention:

1. An adjustable self-balancing transformer comprising a core, primary and secondary windings thereon, tap-off conductors connected to one or more of the intermediate coils of one of the windings, said conductors being tubular, some of which are enclosed by others and separated by insulating tubes and interconnecting means to bridge across said conductors.

2. An adjustable self-balancing transformer comprising a core, primary and secondary windings thereon, tap-off conductors connected to one or more of the intermediate

coils of one of the windings, said conductors being tubular, some of which are inclosed by others and separated by insulating tubes and interconnecting means to bridge across said 5 conductors, the larger conductors being shorter than the contained smaller conductors and the insulating tubes being arranged to expose the ends of the conductors.

3. A series of take-off conductors for self-
10 balancing transformers and the like, some of which are tubular and surround the others, insulating tubes separating said conductors and arranged at their ends to expose the ends of the conductors, said conductors and tubes

being progressively longer from the larger, 15 central inclosing conductor and tube to the outer ends of the device, and connecting means to bridge across the ends of said conductors.

In testimony, that I claim the foregoing as 20 my invention I affix my signature in the presence of two witnesses, this 28th day of August A. D. 1915.

CHESTER H. THORDARSON.
